UNITED STATES PATENT OFFICE.

JOSEPH DE GAETA, OF NEW YORK, N. Y.

DIES FOR MAKING ARTICLES FROM SHEET METAL.

1,161,628.

Specification of Letters Patent. Patented Nov. 23, 1915.

Application filed March 29, 1915. Serial No. 17,640.

To all whom it may concern:

Be it known that I, JOSEPH DE GAETA, a subject of the King of Italy, and a resident of the borough of Brooklyn, county of 5 Kings, and city and State of New York, (having declared my intention of becoming a citizen of the United States,) have invented certain new and useful Improvements in Dies for Making Articles from Sheet 10 Metal, of which the following is a specification.

My improvements are applicable for use in the manufacture of various articles from sheet metal blanks, but are designed more 15 particularly in the present case for, and are herein shown and described as adapted to, the making of corner shields for trunks, boxes, and the like, where angular parts are to be protected and reinforced against the 20 exigencies of rough usage and contact with extraneous objects.

The main object of the invention is the production of the article desired in a cheaper and more effective manner than theretofore,—the product being more perfect and 25 symmetrical in shape, and involving the expenditure of less than one fourth in time, labor and manipulation heretofore involved.

The invention consists in the combination 30 and arrangement of parts hereinafter described and claimed specifically, whereby the sheet metal for each cap or corner shield is first partially drawn into shape centrally, then perforated to form the attachment 35 holes, then severed from the sheet, and then finally fully drawn and stamped into perfect shape,—all these operations being conducted simultaneously in a single press, so that, after the first three preliminary strokes 40 of the plunger and male dies, a perfect corner shield is produced at each stroke of the press.

In the accompanying drawings, Figure 1, is a side elevation of a power press embodying my improvements; Fig. 2, a perspective view of cap or corner shield; Fig. 3, is a diagrammatic representation in series of the successive steps involved in the production of the corner shield according to my 50 method; Fig. 4, a top view of the shield piece as severed from the sheet metal blank preparatory to being subjected to the action of the finishing dies; Fig. 5, is a top view on a reduced scale of the finished corner 55 shield; Fig. 6, is a top view of the gang of female dies; Fig. 7, a sectional elevation

taken mainly on line 7—7 Fig. 6; Fig. 8, is a sectional elevation of the gang of male dies; Fig. 9, a view of the underside thereof.

P, represents a power press of any ordinary or desired construction, p, indicating the reciprocatory plunger to which the gang M, of positive or male dies are rigidly secured, and p', the usual bed upon which the gang of negative or female dies N, are 65 mounted.

The product desired in the present case is shown in Fig. 2,—i. e., a cap or shield S, to be applied to a corner of a trunk, suit case, box, or rectangular receptacle of any kind. 70 These shields have heretofore been made by five separate and distinct manipulations. First, a disk was punched out of a sheet metal blank, and then the cap was struck up at a single blow in a die press, the metal 75 suffering severe strain in the single drawing, resulting in cracking of the apex, puckering of the sides and particularly of the edges of the cap. Next, the three attachment holes s', s', s', for rivets or other means of securing 80 the shield in place for use, were separately punched, thus, as before stated, involving five distinct operations,—the time and labor involved being the principal factor in the cost of the article produced. As 85 millions of these trunk corner caps or shields are made and used every year, even a slight saving in cost of manufacture is an important consideration; and another desideratum is the production of a cap or shield with 90 side walls perfectly smooth and unpuckered, and of uniform surface. This I accomplish by my method and apparatus in such manner that a perfect shield cap is formed at each stroke of the press after the sheet metal blank 95 has been fed into the apparatus by the preliminary steps. Thus in Fig. 3, o, represents the end of a blank ribbon of sheet metal before being fed to the dies; 1, the result of the 100 first feed step; 2, the result of the second; 3, the result of the third; and 4, the result of the fourth, representing of course four reciprocations of the plunger and male dies.

The first operation on the sheet metal strip o, is the formation of the central or incipient depression s, which draws or upsets the metal for approximately one half (more or less) of the final depth of the cup shown in Figs. 2, and 5. The next operation punches the three holes s', s', s', simultaneously; and the next severs the disk, shown in Fig. 4, from the sheet metal blank o,

leaving the hole and scrap o' . This partially cupped and perforated disk shown in Fig. 4, then drops by gravity into position to be acted upon by the finishing dies, from which the finished product is projected in the form shown in Figs. 2, and 5,—this final operation having completed the cupping of the whole disk severed from the sheet metal blank o . It is thus obvious that

10 if a long sheet metal blank ribbon o , is used (and there is no limit in this respect other than that of the length of the ribbon that can be produced for the purpose) after the third intermittent feed step, a complete

15 shield S , will result from each successive stroke of the plunger and male dies M . In order to effect this desirable result I set my dies, both male and female, at an angle say approximately of 45° in the press P , and arrange

20 the preliminary upsetting dies, the perforating dies, and the disk cutting dies in alinement, with the finishing dies at the end of a runway which conducts the perforated disk from the disk-cutting dies to

25 said finishing dies. Thus as shown in the drawings the preliminary male die m , the punches m' , and the disk cutting die m^2 , are arranged in alinement in the platen m^4 , m^{41} , while the finishing die m^3 , is mounted

30 in a rear extension m^{44} , of the platen m^4 , m^5 , representing the platen stem by which the platen is secured to the reciprocating plunger p , of the press. By reference to Fig. 9, in which this stem m^5 , is shown in dotted lines, it will be seen that it occupies a medial position between the finishing die and the alinement of the preceding dies, so that all are adequately supported. In coinciding manner and arrangement the gang N , of

35 40 female dies are positioned in the negative die plates n^4 , n^{41} , which are supported upon the press bed p' . That is to say the preliminary die n , the perforating die n' , and the disk cutting die n^2 , (see Fig. 7,) are arranged in alinement in the plates n^4 , n^{41} , while the finishing die n^3 , is at the rear, connected with the disk-cutting die n^2 , by the gravity guide ways n^{33} , extending rearward and downward from the die base plate n^{42} .

45 50 The platen consists of the upper plate m^4 , integral with the stem m^5 , and the lower plate m^{41} , on which the dies and punch m , m' , m^2 , m^3 , are directly mounted. The preliminary die m is rigidly secured to the plate m^{41} , by a set screw a , and is surrounded by a stripper ring a' , between which and the said plate m^{41} , is interposed an elastic resilient cushion a^2 , preferably although not necessarily of rubber (see Fig. 8.). This stripper a' , holds the sheet metal blank down against the bed plate n , when the plunger p , is depressed. It is suspended on screws a^3 , the shanks of which act as supporting guides free to slide in the plates m^4 , m^{41} , as the elastic resilient cushion a^2 , yields or expands.

The punches m' which form the attachment holes s' , of the corner shield S , are mounted in the lower plate m^{41} , and held in place in their sockets by the upper plate m^4 , of the platen. The disk-cutting die m^2 , is secured to the lower plate m^{41} , by the set screw b ; and the finishing die m^3 , to the extension m^{44} , of the plate m^{41} , by the set screw c . These or any other well known or suitable means of mounting the male dies in the platen may be resorted to as may be found most expedient, as I do not limit myself to these minor details of construction. Similarly the mounting and support of the female dies n , n' , n^2 , and n^3 , may be effected

75 80 in any desired and well known manner. As shown in the accompanying drawings, the said dies are formed in the die plates n^4 , n^{41} , which are held in place on the base plate n^{42} , by means of screw bolts d' , d' , d' , two of which serve to secure the cap plate d^2 , to the die plate n^{41} , in which the perforating die n' , and disk cutting die n^2 , are formed. The preliminary mortise die n , conforms of course to the shape of the male die m ; and it is provided with an ejector e , of well known character which raises the blank out of the socket as the male die m , recedes. A similar ejector e' , is used in connection with the finishing die mortise n^3 . The intermediate mortise perforating die n' , is formed with the triangular recess n'' , to accommodate the incipient draw of the metal blank effected in the preliminary dies m , n , as well as with the holes n^x , n^x , n^x , two of which are shown in dotted lines in Fig. 7 for the accommodation of the punches m' ,—these holes n^x , extending through both the stripping plate d^2 , and the negative die plates n^{41} , and n^{42} , so as to discharge the small disks punched from the blank in the formation of the attaching holes s' , s' , s' , of the corner shield S . The cap plate d^2 , is formed with coincident perforations d^x , for the passage of the punches m , as well as with triangular openings n^{12} , coinciding with triangular recesses n'' , in the die plate n^{41} .

The cylindrical recess of the disk-cutting die n^2 , extends through the bed plate n^{41} , and through the upper portion of the bed plate n^{42} , as shown in Fig. 7, thus leading the severed disk to the guide ways n^{33} , n^{33} , which extend through and from the base plate n^{42} , to the female finishing die n^3 . The cap plate d^2 , is formed with a circular opening n^{22} , coinciding with the die opening n^2 , below so as to admit of the passage of the male die m^3 . The cap plate d^2 , constitutes a stripping plate for the male dies n' , and n^2 .

g , g' , are adjustable gages or stops arranged in conjunction with the finishing die n^3 , to accurately centralize the blank (Fig. 4,) delivered by the ways n^{33} . These gages

g, g, may be supported in any suitable manner on stationary parts of the apparatus, and it is to be understood that the die *n*³, is also supported on the bed of the press in 5 a manner well known in the art.

h', h², h³, are gage stops for positioning the end of the sheet metal blank *o*, with relation to the female dies.

h', and *h²*, are used only in starting the 10 blank *o*, through the press. They each consist of a pin retracted normally by a spring. By pressing in the stop *h'*, temporarily the edge of the blank may be gaged for the dies *m, n*, and released after 15 the stroke of the plunger, when the stop *h'*, will be retracted automatically upon release, so as to be out of the way of the further and continuous feed of the blank *o*. In like manner the gage pin *h²*, 20 may be manipulated with relation to the dies *m', n'*. The stop *h³*, is permanent in position, first acting as a stop for the front edge of the sheet metal blank in the preliminary feed and then as a stop for the 25 corresponding inner edge of each hole *o'*, as the feed of the blank *o*, is continued. Any other desired or equivalent means of gaging the feed of the sheet metal blank *o*, may be substituted if preferred, the means here- 30 in shown being only illustrative of the function performed.

It will be noted that by my apparatus and method of treatment the coupling of the metal is effected only in part by the first 35 dies; the attachment holes are next formed simultaneously in portions of the blank sheet still on the flat, and the disk of the proper size then severed from the sheet, producing a flanged blank like that shown in Fig. 40 4, with the attachment holes *s'*, in the flat flanged portion. Hence the finishing dies perform only the function of bringing the flange portion of the blank Fig. 4, into alignment with the side walls of the depression 45 *s*, formed by the preliminary dies *m, n*, as hereinbefore set forth. Owing to this step by step evolution of the product, the resultant corner shield is free from pucker, corrugation or irregularity of any kind, 50 the surfaces being perfectly even and smooth. Incidentally attention may be called to the fact that by forming the attachment holes *s'*, in the flat portion of the sheet metal blank I am enabled to form them 55 simultaneously and thus eliminate two operations and manipulations heretofore involved in the manufacture of such corner shields. And as, after the front edge of the sheet metal blank has reached and

passed the stop *h³*, the continuous feed and 60 operation of the press produces a perfect corner shield at each reciprocation of the press the economy effected in the cost of manufacture is obvious. It is also obvious that this press and method is applicable to 65 the manufacture from sheet metal of other articles similar in character and requirements of treatment, so that I do not limit myself strictly to the production of corner shields, a distinctive feature of my invention being that I accomplish in one machine and practically in one feed (after 70 start) and manipulation results that have heretofore necessitated the use of four separate machines,—*i. e.*, a cupping machine, 75 and three punching machines to keep up with the production of the cupping machine; and there are other lines of manufacture of sheet metal articles in which equivalent results may be attained by the utilization 80 of the essential features of my invention. Hence,

What I claim as my invention and desire to secure by Letters Patent is,

1. In a power press of the character designated, the combination of a series of male and female dies comprising preliminary upsetting dies, perforating dies, and disk cutting dies arranged in alinement, and finishing dies positioned at the rear of the disk cutting dies and connected therewith by gravity guideways.

2. In a power press of the character designated, the combination of a series of male and female dies mounted at an angle and comprising preliminary upsetting dies, perforating dies, and disk cutting dies arranged in alinement, and finishing dies positioned at the rear of the disk cutting dies and connected therewith by inclined ways, for the 100 purpose described.

3. In a power press of the character designated, in combination, a series of male and female dies set at an inclination and comprising preliminary upsetting dies, perforating dies, and severing dies arranged in alinement, gages for regulating the feed of a strip of sheet metal to the aforesaid dies, and finishing dies arranged at the rear of the severing dies and connected therewith 110 by inclined guide ways, whereby a complete article may be formed at each stroke of the platen.

JOSEPH DE GAETA.
